Fig. 4

FIG. 1 is a bottom perspective view of an illuminator grid panel embodying my new design;

FIG. 2 is a fragmentary top plan view of the grid panel of FIG. 1;

FIG. 3 is an elevation of one edge of the panel of FIG. 1, the remaining edges being similar in appearance; and

FIG. 4 is a fragmentary bottom isometric view, on an enlarged scale, of a corner portion of the grid panel of FIG. 1.

The panel is fragmentarily shown in FIGS. 2 and 4 for convenience of illustration.

I claim:

The ornamental design for an illuminator grid panel, as shown and described.
